TENSIONING DEVICE FOR CABLES,
WIRES, ETC.Donald A. Howard, Worcester, and William N.
Matson, Fitchburg, Mass.

Application February 26, 1951, Serial No. 212,743

6 Claims. (Cl. 24—71.2)

1

This invention relates to a new and improved tensioning device for cables, wires, ropes, etc., the principal object of the invention residing in the provision of a relatively simple and inexpensive device for application to a cable or the like for tensioning the same to any degree desired, and at the same time imparting a resilience thereto preventing breakage due to sharp blows that normally occur to a loose cable when it snaps taut under conditions of relatively high wind, etc.

A further object of the invention resides in the provision of a cable tensioning device as stated above, to which any desired degree of tension is quickly and easily imparted merely by application of the device to the cable and then twisting or rotating a spring arm thereon which gradually twists the cable on a spool-like member increasing the tension and increasing the resilient effect imparted by the device thereto.

Another object of the invention resides in the provision of a plate having spool-like means for receiving a cable or the like in straight relation thereacross, and a spring means secured to the spool-like device and capable of manual rotation for increased tensioning, the spool-like device rotating therewith, said spring having a hook thereon for engagement with the cable at increments of 180°, during the rotation thereof.

Other objects and advantages of the invention will appear hereinafter.

Reference is to be had to the accompanying drawings in which.

Fig. 1 is a plan view of the device shown applied to a cable;

Fig. 2 is a plan view at the opposite side thereof;

Fig. 3 is a diagrammatic view illustrating initial application of the cable to the device;

Fig. 4 shows the first step in tensioning of the cable;

Fig. 5 shows the spool-element partially rotated;

Fig. 6 illustrates a rotation of the spool-like element to approximately 180° from the Fig. 4 position and showing the cable considerably tensioned;

Fig. 7 is a section through the plate and spring illustrating the parts in assembled relation;

Fig. 8 is a side elevational view of the spool-like member;

Fig. 9 is a plan view thereof;

Fig. 10 is a plan view of a modification; and

Fig. 11 is an edge view thereof.

In erecting masts, stacks, flag poles, etc., the use of guy wires is a commonly accepted procedure, finding wide spread use in many relations,

but it has always been a problem to impart the correct tension to the guy wires, particularly with relation to those at opposite sides of the mast erected. If a guy wire is slightly loose or a little too tight, it will snap under condition of high winds, particularly gusty winds, if either too much tension is applied to the guy wire in the case where it is too tight, or a sharp blow is imparted thereto in excess of the strength thereof, in the case of a wire that is loose. The present device overcomes all of the difficulties in the tensioning of such wires, but is also useful in many other relations, particularly in tightening clothes lines, tie down wires, cables of all kinds, etc.

Referring to Figs. 1 and 2, the present device comprises a plate indicated at 10, this plate having a short central slot shown at 12 through which projects the loop 14 of a spool-like member 16. The spool-like member 16 is preferably made of wire and extends away from the loop 14 in two runs, see particularly Figs. 7 and 8, these runs being bent to form a pair of loop-like feet 18 and 20. In general, the spool-like member 16 is thus rotationally fixed relative to plate 10 although this is not a necessary feature of the invention, but is the preferred form.

The two runs of the loop 14 may be provided with projections 22, and these runs may be springy if desired so that when the loop 14 is projected through the slot 12, it will impinge on and be held thereto as seen in Fig. 7 with the feet 18 and 20 spaced from plate 10.

The loop 14 extends slightly to the opposite side of plate 10 and provides a holding means for the double hooked free end 24 of a spiral spring member 26, the other end of which terminates in a long straight run 28 having a hook 30 at the free end thereof.

It will be seen that the straight run 28 of the spring may be moved counterclockwise in Fig. 2 and that if the plate 10 or the loop 14 is held against moving it, the spring 26 will wind up and become tensioned, and will tend resiliently to rotate reversely in a clockwise direction.

With the spool-like member as shown in Fig. 3, the device is applied to a cable 31 with the latter running straight through the loops as at 32 in Fig. 7, the cable being held at both ends, as to a mast or the like and to a support, clamp or clevis.

Then by grasping the long run 28 of the spring as a handle, and rotating in the proper direction, as illustrated in Fig. 4, the cable 31 is held between the two runs of the spool-like member on which appear projections 22. Further rotation results in a kink in the cable 31 as appears in Figs.

5 and 6, and it will be seen that the cable has been considerably shortened, i. e., tension in the Fig. 6 position.

If the hook 30 is slipped over a part of the now tensioned cable, the entire device is held in the position described with tension on the cable or wire in the direction of the arrows A in Fig. 6. It will be clear that excess or sudden increased pressure being applied in the direction of these arrows, the tendency is for the spool-like member to be rotated in a counterclockwise direction in Fig. 6 although this would be in a clockwise direction in Fig. 2. The resilience in the spring 26 resists this movement although it allows it to take place to a limited degree, depending on the degree of tension originally applied to the spring.

This action will clearly provide against any breakage of the cable because of the fact that a "give" is present if necessary, but under ordinary conditions, the cable is maintained tight by the spring.

It is to be noted that the device may be rotated further, i. e., another 180° in a clockwise direction in Fig. 1, increasing the tension and lapping the wire around the spool-like member on the runs forming the loop 14. It will be seen that any desired tightness can be applied to the cable after the slack is mostly removed by the operation of the device as above stated. The main purpose of plate 10 is to prevent canting of the parts and interference of the cable and spring.

A modified form of the invention is shown in Figs. 10 and 11 wherein the plate and the spool-like member are combined in a single element. This comprises a plate 34 having a plurality of segmental punched out portions 36 forming a kind of rim connected by diametrical arms 38. The segmental portions are pressed downwardly as shown in Fig. 11 forming a plurality of radially extending shelves or projections 40. The center of the device at the junction of arms 38 is raised up as at 42 to form a hook or the like for the reception of the free end 24 of the spring in the same manner that this element is hooked into loop 14.

The arms or shelves 40 receive the wire as a spool substantially as above recited; and as illustrated in Figs. 3 to 6, since the wire may initially be laid in diametrically of the plate beneath two aligned arms 38, and between parts 40 as illustrated at 44, and then upon rotating the spring as described above, the device may be used in the same way.

It will be seen that this invention provides a relatively simple device for applying tension in steps of any adjustment desired to cables, ropes, wires, etc. The device always maintains the cables, etc., under yielding tension so that a sudden snap or sharp blow cannot part the cable, as will be the case if no give were present; yet at the same time, the cable is maintained taut with no slack and under varying degrees of adjustment of tension.

Cables under stress always have a degree of inherent stretching which may be caused by unusually hot weather when the normal expansion on long cables is noticeable, but the novel tensioning device will wind up slack to keep the cable taut, and also the tensioner pays out cable when the same is extremely cold and contracted, and so the tensioner will keep a very good aver-

age tightness for all weather conditions on cables.

No tools of any kind are needed to install the new tensioner and it eliminates the use of turnbuckles and ratchet arrangements besides adding the resilient "take up" and "give" features.

Using bent wire for a spool allows the cable to be wound on a small diameter thus giving a small movement on the spool as compared with the mechanical advantage provided by the long hook arm on the spring. With very little work used in rotating the hook, considerable tension may be applied to the cable. This permits a minimum of weight and size for all parts of the device and allows the operator to get any desired tightness on the cable with very little effort.

Having thus described our invention and the advantages thereof, we do not wish to be limited to the details herein disclosed otherwise than as set forth in the claims, but what we claim is:

- 20 1. A cable tensioning device comprising a plate, a loop thereon, a pair of axially extending elements on the plate, a spring secured to the loop, said elements receiving a cable therebetween substantially diametrically of the plate,
- 25 2. The device of claim 1 wherein the spring extending substantially radially of the plate and capable of rotating the plate and winding the cable on the elements by rotation thereof, and means to secure the extending portion of the spring to the cable.
- 30 3. The device of claim 1 wherein the loop and axially extending elements form parts of a bent wire, the loop extending through the plate to one side thereof and the elements appearing at the opposite side of the plate.
- 35 4. The device of claim 1 wherein the loop and axially extending elements form parts of a bent wire, the loop extending through the plate to one side thereof and the elements appearing at the opposite side of the plate, and means on the loop locating the bent wire in desired position relative to the plate.
- 40 5. The device of claim 1 wherein the loop and axially extending elements form parts of a bent wire, the loop extending through the plate to one side thereof and the elements appearing at the opposite side of the plate, and means on the loop locating the bent wire in desired position relative to the plate.
- 45 6. The device of claim 1 wherein the loop and axially extending elements form parts of a bent wire, the loop extending through the plate to one side thereof and the elements appearing at the opposite side of the plate, and means on the loop locating the bent wire in desired position relative to the plate.
- 50 7. The device of claim 1 wherein the loop is struck up from the plate and the elements form parts thereof bent outwardly to the opposite side surface of the plate.
- 55 8. The device of claim 1 wherein the loop is struck up from the plate and the elements form parts thereof bent outwardly to the opposite side surface of the plate, and pressed out feet on the elements extending generally radially of the plate in spaced relation thereto.
- 60 9. The device of claim 1 wherein the loop is struck up from the plate and the elements form parts thereof bent outwardly to the opposite side surface of the plate, and pressed out feet on the elements extending generally radially of the plate in spaced relation thereto.

DONALD A. HOWARD,
WILLIAM N. MATSON.
